UNITED STATES PATENT OFFICE.

FREDERICK E. VOORHIES, OF TULSA, OKLAHOMA.

GAS CONDENSER.

Application filed April 28, 1921. Serial No. 465,165.

To all whom it may concern:

Be it known that I, FREDERICK E. VOORHIES, a citizen of the United States, residing at Tulsa, in the county of Tulsa and State of Oklahoma, have invented certain new and useful Improvements in Gas Condensers; and I do declare the following to be a full, clear, and exact description of the invention, such as will enable others skilled in the art to 10 which it appertains to make and use the same.

My invention relates to improvements in gas condensers especially adapted for producing casinghead gasoline.

15 One object of the invention is to provide a novel form of gas condenser which will condense a greater percentage of gasoline from casinghead gas, per horse power of energy expended, than any of the methods now in 20 use.

In attaining the above end, other objects are to provide novel means for carrying out a more effective condensing operation on any uncondensed gas which passes through 25 the main set of condensing coils; and to provide both the main and supplemental coils with inner coils for the condensation of any gases which pass uncondensed to the accumulating tank into which the apparatus dis- 30 charges.

With the foregoing and minor objects in view, the invention resides in the novel construction, combination and association of parts hereinafter described and claimed, the 35 descriptive matter being supplemented by the accompanying drawings.

Figure 1 is a diagrammatic elevation of the entire apparatus.

Figure 2 is an end view.

40 Figure 3 is an end elevation of one of the sections of the cooling coils.

Figure 4 is a central longitudinal section taken on the plane of the line 4—4 of Fig. 3.

Figure 5 is a horizontal sectional view 45 taken on the plane of the line 5—5 of Fig. 4.

Figure 6 is a central vertical longitudinal section of the saturating tank.

Figure 7 is a horizontal section taken substantially on the plane of the line 7—7 of 50 Fig. 6.

In the drawings above briefly described, the numerals 1 designate a plurality of vertical coils in which the main condensing process is effected, the inlet ends on the coils 55 1 being connected by piping 2 with a header

3, said piping being provided with control valves 4, while the header 3 is equipped with a pressure relief valve 5. A pipe 6 leads to the header 3 from a saturating tank 7 whose lower end is provided with an inlet 8 through which hot gases from a high stage compressor, enter the tank 7. In this tank, the gases are saturated with gasoline which is supplied to said tank through a pipe 10, which pipe delivers onto the uppermost of a series of inclined partitions 9 which are disposed in staggered relation within the tank 7, the other edges of said partitions being secured in liquid tight contact with the wall of the casing, while the inner edge portions of said partitions are free and are disposed in slightly overlapping relation, so that the gasoline will drip from each partition onto the partition immediately below. The gases entering through the pipe 8 zig zag upwardly through the tank 7 and must therefore necessarily travel through the spray of gasoline dripping from the several partitions or baffles 9, the result being that these gases are thoroughly saturated before they 75 enter the header 3 and travel from this header through pipe 2 and coils 1.

During their passage through the coils 1, the gases are greatly condensed and the liquid gasoline thus formed, together with any uncondensed gases, flows from the coils 1 through pipes 11 and control valves 12, to a header 13. From the lower portion of this header, a pipe line 14 leads to a suitable accumulating tank (not shown) so as to carry 90 the gasoline to this tank. The inlet end of the pipe line 14 is tapped by the inlet end of pipe 10, which pipe is slightly inclined so as to supply the saturating tank 7 with gasoline from the pipe line 14. Pipe 10 is preferably provided with a control valve 15.

Positioned above the coils 1, are a plurality of supplemental cooling coils 1^a which are adapted to condense the greater part of the gases which enter the header 13 without 100 being condensed in the coils 1. These gases rises from the header 13 through a pipe 16 and control valve 17 to a connection 18, which header is connected by pipes 19 with the inlet end of the coils 1^a. The outlet ends of these coils communicate with pipes 20 having control valves 21, said pipes leading downwardly to a connection 22 which communicates with the pipe line 14 beyond the header 13. It thus follows that the liquid 110

condensed in the coils 1^a will be discharged into the pipe line 14 and will travel there through to the accumulating tank.

Attention may here be directed to the fact 5 that the coils 1^a are immediately over the coils 1 and the cooling water is supplied first to the coils 1^a and then to the coils 1, the result being that the coils 1^a will have greater condensing efficiency than the other 10 coils 1. A plurality of perforated troughs 23 are employed to spray the cold water over the coils 1^a, this water being caught in other troughs 24 which discharge onto the coils 1. At the lower ends of coils 1, the water is collected 15 in a main trough 25 and is then cooled and returned to the troughs 23 in the usual or any adequate manner.

Experience has shown that an appreciable amount of uncondensed gas will reach the 20 accumulating tank with the gasoline, but instead of permitting this gas to go to waste, I provide further means for condensing the same. A pipe line 26 having a control valve 27, leads from the accumulating tank to the 25 inlet ends of relatively small coils 28 which are positioned in the coils 1^a, the outlet ends of said coils 28 being connected by pipes 29 with a header 30 adjacent the header 13, said pipes 29 being provided with appropriate 30 valves 31. By means of horizontal pipes 32 and control valves 33, the header 30 communicates with a plurality of coils 34 which extend through the coils 1, the outlet ends of these coils being placed in communication 35 with a header 35, by means of appropriate valves 36. An outlet pipe 37 leads from the header 35.

When first operating the apparatus, it is advisable to prime the saturating tank in 40 any suitable manner so that the first gas to enter will be saturated as well as that which is supplied to the apparatus after the latter has condensed some gasoline to be returned to the tank 7 through the pipe 10. 45 By thus saturating the gases, they will condense much more readily than when the common methods are used. The saturated gases pass from the tank 7 through the pipe 6, header 3, valves 4 and pipes 2, to the inlet 50 ends of the coils 1. The gases travel through these coils around the inner coils 34 and a large proportion of said gases is condensed. The gasoline thus formed, together with any uncondensed gases, passes through the pipes 55 11 and valves 12 into the header 13. The gasoline flows from this header through the piping 14 into the accumulating tank and a small quantity passes through the pipe 10 to the saturating tank 7. The uncondensed 60 gases rise through the valve 17 and the pipe 16 to the header 18 and from this header, the gases pass through the pipes 19 to the coils 1^a, the latter being at a much lower temperature than the coils 1, due not only to the 65 cooling means provided, but to the fact that

the hot gases entering the apparatus never come into engagement with said coils 1^a. Their cooling efficiency is thus much greater than the coils 1 so that most of the gases which have escaped said coils 1, will be condensed to gasoline in the coils 1^a. From these coils, the condensate flows through the pipes 20 and valves 21 to the header 22 and from this header it enters the accumulating tank through the piping 14.

Any gases accumulating in the tank will discharge through the pipe line 26 and will pass through the small coils 28 in the coils 1^a, leaving these coils and travelling through the pipes 29 and valves 31 to the header 30. From this header, the gases and any liquid which has been condensed therefrom, pass through the pipes 32 and valves 33 to the coils 34, which coils discharge into the header 35 through the valves 36. The condensate is carried off through the outlet pipe 37 and if any gas remains uncondensed it is allowed to escape as it is proven beyond a doubt that it cannot be profitably condensed.

The apparatus is comparatively simple and inexpensive, and requires nothing but wellknown condenser parts and connections in its manufacture, yet is much more efficient than condensers now commonly used. By employing the device, a great saving is effected over apparatuses now used, which not only means a less expensive product, but conservation to a large extent of the natural resource from which the gasoline is condensed.

Since excellent results may be obtained from the details disclosed, they may well be followed, but within the scope of the invention as claimed, numerous minor changes may be made.

I claim:

1. A condensing apparatus comprising a pair of independent condensers of relatively low and high efficiency respectively, a condensate outlet from the low efficiency condenser, a gas passage leading from said condensing outlet to said high efficiency condenser, and an outlet from the last named condenser independent of the low efficiency condenser and leading to said condensate outlet.

2. A gas condensing apparatus comprising a condenser having a passage through which the gas passes, said passage having an outlet adapted for connection to an accumulating tank, and piping within said passage adapted for connection with the accumulating tank to carry off and condense any gases given off from the accumulated liquid.

3. A condensing apparatus comprising main and supplemental condensing coils of relatively low and high efficiency respectively, a gas inlet into said main condensing coil, a condensate outlet leading from said coil and adapted for communication with an

accumulating tank, a gas conducting passage leading from said condensate outlet to said supplemental condensing coil, an outlet passage from said supplemental condensing coil to said condensate outlet at a point spaced outwardly from said first named gas conducting passage, relatively small coils within said main and supplemental coils and

communicating with each other, a passage leading to one relatively small coil and 10 adapted to carry gas thereto from the accumulating tank, and an outlet from the other small coil.

In testimony whereof I have hereunto set my hand.

FREDERICK E. VOORHIES.
